UNITED STATES PATENT OFFICE.

FLORENCE KYLE WATSON, OF BLUEFIELD, WEST VIRGINIA.

DESIGN FOR DOLL.

Application filed July 27, 1923. Serial No. 6,883. Term of patent 14 years.

To all whom it may concern:

Be it known that I, FLORENCE KYLE WATSON, a citizen of the United States of America, residing at Bluefield, in the county of Mercer and State of West Virginia, have invented a new, original, and ornamental Design for Doll, of which the following is a specification, reference being had to the accompanying drawings, forming a part hereof.

I claim:

The ornamental design for doll as shown.

FLORENCE KYLE WATSON.
